UNITED STATES PATENT OFFICE.

ANTOINETTE LOUISE SMITH, OF NORWOOD, OHIO.

PASTE HOLDING AND APPLYING DEVICE.

No. 823,298.

Specification of Letters Patent.

Patented June 12, 1906.

Application filed December 22, 1904. Serial No. 237,907.

To all whom it may concern:

Be it known that I, ANTOINETTE LOUISE SMITH, a citizen of the United States of America, and a resident of Norwood, in the county 5 of Hamilton and State of Ohio, have invented certain new and useful Improvements in Paste Holding and Applying Devices, of which the following is a specification.

This invention relates to certain improvements in paste-applying devices such as are especially designed and adapted for use in connection with library paste and the like for applying the same to the surfaces to be pasted or cemented; and the object of the 10 invention is to provide a device of this character of a simple and inexpensive nature which shall be adapted for long-continued use without liability of becoming clogged with the dried paste, the preferred form of 15 the improved paste-applying device comprising a daubing and spreading means and a paste-receptacle, which latter may be replenished from time to time as the same becomes emptied, so that the utility of the 20 device is greatly increased.

The invention consists in certain novel features of the construction, combination, and arrangement of the several parts of the improved paste-applying device whereby 25 certain important advantages are attained and the device is rendered simpler, cheaper, and otherwise better adapted and more convenient for use, all as will be hereinafter fully set forth.

30 The novel features of the invention will be carefully defined in the claims.

In the accompanying drawings, which serve to illustrate the invention, Figure 1 is 35 an elevation showing a paste-applying device constructed according to my invention, and Fig. 2 is a similar view of the device with its cap or cover removed. Fig. 3 is an enlarged fragmentary sectional view taken axially through the upper parts of the improved paste-applying device and illustrating certain details of construction to be hereinafter referred to.

In the views, 1 indicates a collapsible 40 paste-receptacle, preferably in the form of a bulb of soft rubber or similar compressible substance, having its upper part provided with a reduced tubular integral nipple 2, within which is adapted to be held a tubular spreader 3, of metal, hard rubber, or similar 45 substance, adapted by its insertion within the

bulb-nipple 2 to prevent collapse thereof when the paste daubing and spreading means is in position, so that a secure attachment of said means to the bulb may be effected, as will be hereinafter explained. Said spreader 60 or thimble 3 is of sufficient internal diameter to permit convenient filling of the bulb 1 from the collapsible tubes in which paste is commonly sold, and the upper end of the tubular spreader or thimble 3 is provided 65 with a flange 4, outwardly extended and overlying the edge of the bulb-nipple 2 for retaining the spreader in position.

5 indicates a socket carried by the metallic shell or casing 6 of the paste daubing and spreading means and of an internal diameter adapted to receive within it the compressible bulb-nipple 2 for the attachment of the paste daubing and spreading means to the said bulb or receptacle 1, and said socket 5 is preferably 70 integrally formed with said metallic shell or casing 6, screw-threads being spun or otherwise produced in the walls of said socket, so that when the socket is in position over the bulb-nipple 2 the said screw-threads will sink 75 into the compressible material of which the bulb-nipple 2 is formed, as shown in Fig. 3, so as to securely hold the paste daubing and spreading means to the receptacle 1, while permitting of ready detachment of said paste 80 daubing and spreading means when it is desired to replenish the receptacle.

The metallic shell or casing 6 is outwardly directed into an annular flange at its central portion, and it tapers at its upper portion 90 into a conical integral nipple 7, over which latter is adapted to be slipped, as seen in Fig. 1, a cap or cover 9^a of a size to house within it the paste daubing and spreading sponge or part 8, which, as seen in Figs. 2 and 3, is carried above the nipple 7, so that when said cap or cover 9^a is in position the air will be excluded, and the paste within the pores of the spongy paste daubing and spreading part 8 will be prevented from drying and 95 hardening and clogging the device for later use.

The paste daubing and spreading part 8 is 100 preferably formed from a rounded piece of spongy rubber, the pores of which are adapted for the flow of the paste through them when pressure is brought to bear upon the collapsible paste-receptacle 1 in the use of the device, and within said spongy part 8 is inserted a paste-supply tube 9, the upper end 105

of which is incased within the central portion of the rubber sponge and the lower portion of which is adapted to project downward within the spreader or thimble 3, as indicated 5 at 14 in Fig. 3, so that the paste will be forced from the receptacle 1 upward through the supply-tube 9 and will be discharged from said tube to the interstices or pores of the spongy paste daubing and spreading part 10 8, through which pores said paste will pass to the surface over which the part 8 is rubbed or pressed. 10 indicates the bore of the tube 9.

The lower portion of the spongy paste 15 daubing and spreading part 8 is extended down within the nipple 7 of the shell or casing and within said nipple is made to inclose or incase the supply-tube 9, a thread 11 or equivalent device being wrapped around 20 said lower portion of part 8, so as to hold the same securely to the tube 9, as shown in Fig. 3, and for the attachment of the part 8 and tube 9 within the shell or casing of which the body portion is formed I provide within the 25 hollow of said shell or casing, as shown at 12, a filling of cement or other plastic substance, by means of which a secure bond is effected between the part 8 and tube 9 and the shell or casing of the paste daubing and spreading 30 means. This filling 12 is expanded within the hollow of the flange 6, so as to effectively prevent the accidental separation of the parts.

From the above description of my improvements it will be apparent that the paste-applying device constructed according thereto is capable of some modification without material departure from the principles and spirit of the invention, and for this reason I 35 do not wish to be understood as limiting myself to the precise form and arrangement of the several parts of the device as herein set forth in carrying out my invention in practice.

Having thus described my invention, what 45

I claim, and desire to secure by Letters Patent, is—

1. A paste-applying device comprising a collapsible receptacle formed from soft rubber and having a soft-rubber neck or nipple 50 integrally formed on it, a shell having paste daubing and spreading means at its upper part and, at its lower part, an interiorly-screw-threaded socket in which said nipple is adapted to be received and also adapted to receive paste from said collapsible receptacle, and means in the nipple for distending it and simultaneously holding the soft-rubber walls thereof engaged with the interior screw-threads of said lower part. 6c

2. The combination of a soft-rubber bulb having an integral neck or nipple at its upper part, a tubular spreader of hard material inserted within said neck or nipple, and a tubular shell provided, at its upper portion, with 65 paste daubing and spreading means and, at its lower portion, with a socket, the walls of which latter have integral screw-threads for engagement in the said soft-rubber neck or nipple to contain and hold said paste daubing 70 and spreading means detachably upon the bulb.

3. The combination of the casing or shell having at its lower part means of attachment to a paste-receptacle, a spongy part extended 75 above said casing or shell with a lower portion housed therein, a paste-supply tube the upper end of which is adapted for communication with said spongy part and the lower end of which is adapted for communication 80 with a paste-receptacle to which the casing or shell is attached and a filling within the hollow of the shell or casing for holding the spongy part in relation thereto.

Signed at Cincinnati, Ohio, this 19th day 85 of December, 1904.

ANTINETTE LOUISE SMITH.
